(57) **CLAIM**

The ornamental design for a tongue scraper, as shown and described.

DESCRIPTION

FIG. 1 is a top, left side perspective view of my tongue scraper;

FIG. 2 is a rear perspective view thereof;

FIG. 3 is a top side elevational view thereof;

FIG. 4 is a rear side elevational view thereof;

FIG. 5 is a left side elevational view thereof;

FIG. 6 is a right side elevational view thereof;

FIG. 7 is a top, left side perspective view of an alternative embodiment of my tongue scraper, the shading denoting a contrast in appearance;

FIG. 8 is a rear perspective view thereof;

FIG. 9 is a top side elevational view thereof;

FIG. 10 is a rear side elevational view thereof;

FIG. 11 is a left side elevational view thereof; and,

FIG. 12 is a right side elevational view thereof.
